(57) **CLAIM**

(21) Appl. No.: **29/245,242**

The ornamental design for a support head for optical and photographic equipments, as shown and described.

(22) Filed: **Dec. 21, 2005**

DESCRIPTION

(30) **Foreign Application Priority Data**

Jun. 21, 2005 (EM) 000358841

(51) **LOC (8) Cl.** **16-05**

FIG. 1 is a perspective view from the top right of a support head for optical and photographic equipments showing my new design.

(52) **U.S. Cl.** **D16/243; D16/245**

FIG. 2 is a perspective view from the top left of the support head of FIG. 1;

(58) **Field of Classification Search** D16/237,

FIG. 3 is a top plan view of the support head of FIG. 1;

D16/242, 243–245; 224/908; 248/176.1,

FIG. 4 is a bottom plan view of the support head of FIG. 1;

248/177.1, 178.1, 187.1, 183.1, 183.2; 348/373;

FIG. 5 is an elevation view from the right side of the support head of FIG. 1;

352/243; 396/419, 420, 428

FIG. 6 is an elevation view from the left side of the support head of FIG. 1;

See application file for complete search history.

FIG. 7 is a rear elevation view of the support head of FIG. 1; and,

(56) **References Cited**

FIG. 8 is a front elevation view of the support head of FIG. 1.
